UNITED STATES PATENT OFFICE

2,156,744

FITTING CLEANER

Henry J. Smith, Great Neck, N. Y.

Application December 6, 1938, Serial No. 244,269

1 Claim. (Cl. 51—187)

This invention appertains to new and useful improvements in tools for conveniently cleaning copper sweat fittings and various other types of fittings.

5 The principal object of the present invention is to provide a cleaner of the character stated which will be handy to use and in structure is simple and not susceptible to the ready development of defects.

10 Other objects and advantages of the invention will become apparent to the reader of the following specification.

In the drawings—

15 Figure 1 represents a side elevational view with a portion of the fitting broken away to disclose the tool inserted therein.

Figure 2 is a longitudinal sectional view through the tool.

20 Figure 3 is a fragmentary longitudinal sectional view showing the retaining arm in disengaged position.

Figure 4 is a section on the line 4—4 of Figure 1.

25 Figure 5 is an end elevational view of the cleaner.

Figure 6 is a perspective view of a roll of sandpaper or the like.

Referring to the drawings, wherein like numerals designate like parts, it can be seen that the invention consists of the cylindrical head 5 having the V-shaped notch 6 extending longitudinally thereof and at its free end merging with the inwardly extending groove 7 terminating at the end pocket 8, through which the pin 9 is disposed and which serves to receive the eye end 10 at the foot portion 11 of the arm 12, the foot portion 11 being disposed in the groove 7 while the arm 12 is disposed in the groove 6 so as to engage over the end portions of a sheet 13 of sand-paper or the like, and retain the sheet of sand-paper circumscribing the head 5. The head is reduced as at 14 and extended to provide the threaded shank 15, the groove 6 extending across the reduced portion 14 and terminating at 45 a midpoint of the shank 15. The arm 12 is offset as at α to follow the reduction 14 and the

portion thereof extending from the off-set α and denoted by the reference character b is provided with teeth 16 which will match the threads of the shank 15 so that the knurled nut 17 can be fed on the shank 15 and over the arm extension b so as to fasten the arm in sand-paper-holding position as shown in Figures 1 and 2.

The free end of the shank 15 is beveled as at 18 and is seated in the tapered recess 19 of the knurled knob 20. Obviously, by engaging the tool into a fitting 21 in substantially the manner shown in Figure 1, the tool can be rotated for thoroughly cleaning the interior of the fitting.

It is preferable that the arm 12 be of V-shape or triangular shape in cross section.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is—

A tool of the character described comprising an elongated body having a longitudinally extending slot therein, one end of the body being formed with a pocket, a channel extending from the pocket and communicating with the slot, an L-shaped arm having its lower portion disposed into the pocket, a pin extending across the pocket and through the lower end of the L-shaped arm, the horizontal portion of the arm being adapted to be disposed in the channel while the vertical portion is disposed in the slot, the upper portion of the arm provided with serrations at its outer side, said elongated body being provided with threads at its portion adjacent the serrations of the arm and with which the serrations are matchable, a nut feedable on the threaded portion of the body and upper portion of the arm, and a strip of abrasive material adapted to be disposed around the body and across the said slot, and holding means on the body for holding the arm disposed into the slot and against the said strip.
